2 Claims. (Cl. 317—147)

(Granted under Title 35, U.S. Code (1952), sec. 266)

The invention described herein may be manufactured and used by or for the United States Government for governmental purposes without payment to me of any royalty thereon.

The purpose of this invention is to provide a command circuit that will respond only to a command signal meeting the following conditions: (1) An alternating signal of predetermined frequency pulsed "on" and "off" periodically; (2) A ratio of "on" time to "off" time exceeding a predetermined value; (3) An "on" time less than a predetermined amount; (4) An "off" time less than a predetermined amount; and (5) An "off" time greater than a predetermined amount. The necessity for satisfying all of these conditions insures a high degree of protection against false operation of the command circuit.

The invention will be explained in detail with reference to the specific embodiment thereof shown in the accompanying drawing in which

FIG. 1 shows the general form of the command signal, and

FIG. 2 is a schematic diagram of a command circuit in accordance with the invention.

Referring to the drawing, when an alternating current command signal of the type shown in FIG. 1, and meeting the five requirements defined above, is applied to terminal 1, switch 2 is actuated to its closed position. This switch may be included in any external circuit which it is desired to control by the command signal.

The circuit of FIG. 2 is designed for use with command signals in the audio frequency range. Relay K₁ may be of the vibrating reed type having an actuating coil 3, a stationary contact 4 and a movable contact 5 in the form of a vibrating reed. An alternating current in coil 3 causes the reed to vibrate. The amplitude of the vibration, however, will be sufficient for reed 5 to touch contact 4 only when the frequency of the energizing current equals, or very nearly equals, the resonant frequency of the reed. Consequently, a command signal, having substantially the same frequency as the natural frequency of the reed, will cause contacts 4—5 to make and break at an audio rate, resulting in a pulsed direct current through the coil of K₂ of sufficient average value to actuate this relay.

Closing the contacts of K₂ connects C₁, which has previously charged through R₁ to the potential of terminal 6, across the coil of K₃ allowing this condenser to discharge through the coil and actuate K₃. The charge in C₁ is only enough for a momentary actuation of the relay and the resistance of R₁ is high enough that the current flow to the coil of K₃ is below that required to hold the relay in the energized state. However, when K₃ is energized by C₁, a holding circuit is established from the coil of K₃ through the contacts of K₂ and contacts 1—2 of K₃ to condenser C₂. This condenser is larger than C₁ and was previously charged through contacts 1—2 to the voltage of terminal 6. The discharge of C₂ through the coil of K₃ holds this relay energized either until K₂ opens or until the discharge current has fallen to the dropout level of the relay. It is therefore seen that K₃ can not remain energized for longer than a fixed interval determined principally by the size of C₂.

The R₂—C₂ circuit is designed to have a very short time constant so that C₂ recharges almost immediately upon release of K₃ and closure of contacts 3—2. For

2

example, R₂ may have a resistance of 47 ohms and C₂ a capacity of 20 microfarads, giving a time constant of about 0.5 millisecond.

The R₁—C₁ circuit is designed to have a relatively long time constant as compared to the R₂—C₂ circuit. For example, R₁ may have a value of 68000 ohms and C₁ a capacity of 0.5 microfarad, giving a time constant of 34 milliseconds. Since C₁ can not charge while the contacts of K₂ are closed, the time constant of this circuit determines the minimum "off" period of the command signal. If the command signal has an "off" period less than this minimum, including a zero "off" period (continuous signal), only a single actuation of K₃ can occur.

During the time that K₃ is actuated, heating element 7 of thermal switch 2 is energized through contacts 4—5. This switch is designed so that, when pulses of current of a constant specified amplitude are periodically applied to it, the ratio of the pulse duration to the interval between pulses, i.e., the ratio of the "on" time of the energization to the "off" time, must exceed a predetermined value to produce enough heating to cause the switch contacts to close. For example, the predetermined value of this ratio may be unity. Stated in other words, the average value of the pulsed current flow in element 7 must exceed a predetermined amount in order to close the switch contacts.

Returning to the five previously listed conditions that must be met by the command signal before it is capable of causing actuation of switch 2, the features of the circuit responsible for these requirements are as follows:

Condition 1: The signal must be an alternating signal of the required frequency to actuate relay K₁. The signal must be pulsed in order to secure energization of thermal switch 2 over a sufficient period of time to cause its contacts to close. If the signal were continuous, the contacts of K₂ would remain closed and only a single actuation of K₃, applying only a single pulse of energy to switch 2, would occur.

Condition 2: Since, for switch 2, the ratio of the heating current pulse duration to the interval between current pulses must exceed a predetermined value to operate the switch and since the characteristics of the K₃ circuit prevent this ratio from ever exceeding the "on" time to "off" time ratio of the command signal, it follows that the latter ratio must exceed the predetermined ratio for the switch 2 in order to effect operation of the switch.

Condition 3: As already explained, relay K₃ will not remain energized longer than a fixed interval determined mainly by the size of C₂. The maximum duration of energizing pulse for switch 2 equals this fixed interval. For this maximum pulse duration, there is a corresponding maximum interval between pulses above which the required energization of switch 2 will not be achieved. If the "on" period of the command signal exceeds the K₃ fixed interval plus the above defined maximum interval between pulses, switch 2 will not be actuated.

Condition 4: If the command signal "off" time exceeds the above defined maximum interval between pulses, actuation of switch 2 will not occur.

Condition 5: If the command signal "off" time is less than the time required for C₁ to receive sufficient charge to actuate K₃, only a single actuation of K₃ will occur and, consequently, switch 2 will not be actuated.

I claim:

1. A command circuit comprising: frequency sensitive means, having a set of normally open contacts, for receiving a command signal and closing said contacts when said signal has a predetermined frequency; a relay having two sets of normally open contacts, a set of normally closed contacts and an actuating coil therefor; first and second capacitors; a source of direct current; means including a resistor for connecting said first capacitor across

said source; means including the contacts of said frequency sensitive means for connecting the first capacitor across the coil of said relay; means including the normally closed contacts of said relay for connecting the second capacitor across said source; means including one set of normally open contacts of said relay and the contacts of said frequency sensitive means in series for connecting the second capacitor across the coil of said relay; a current actuated switch responsive only to an energizing current having an average value in excess of a predetermined amount; and means for applying an energizing

4
current to said switch through the other set of normally open contacts of said relay.

2. Apparatus as claimed in claim 1 in which said switch is a thermal switch having a heating element 5 through which said energizing current passes.
